(57) CLAIM

The ornamental design for a shaft for an exhaust gas recirculation valve, as shown.

DESCRIPTION

FIG. 1 is a front, top and left side perspective view of a shaft for an exhaust gas recirculation valve, showing my new design;

FIG. 2 is a front elevational view thereof, a rear side being the same image thereof;

FIG. 3 is a right side elevational view thereof, the left side being the same image thereof;

FIG. 4 is a bottom plan view thereof; and,

FIG. 5 is a top plan view thereof.
